(57) **CLAIM**

The ornamental design for a two-piece insole, as shown and described.

DESCRIPTION

FIG. 1 is a front, top perspective view of a two-piece insole showing our new design;

FIG. 2 is a top plan view of FIG. 1;

FIG. 3 is a bottom plan view of FIG. 1;

FIG. 4 is a right elevational view of FIG. 1;

FIG. 5 is a left elevational view of FIG. 1;

FIG. 6 is a front elevational view of FIG. 1;

FIG. 7 is a back elevational view of FIG. 1;

FIG. 8 is a front, top perspective view of the chassis portion of our new design;

FIG. 9 is a top plan view of FIG. 8;

FIG. 10 is a bottom plan view of FIG. 8;

FIG. 11 is a right elevational view of FIG. 8;

FIG. 12 is a left elevational view of FIG. 8;

FIG. 13 is a front elevational view of FIG. 8;

FIG. 14 is a back elevational view of FIG. 8.

FIG. 15 is a front, top perspective view of the shell portion of our new design;

FIG. 16 is a top plan view of FIG. 15;

FIG. 17 is a bottom plan view of FIG. 15;

FIG. 18 is a right elevational view of FIG. 15;

FIG. 19 is a left elevational view of FIG. 15;

FIG. 20 is a front elevational view of FIG. 15; and,

FIG. 21 is a back elevational view of FIG. 15.

The portions of the two-piece insole shown in broken lines form no part of the claimed design.

1 Claim, 15 Drawing Sheets
